UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Application filed November 30, 1923. Serial No. 677,828.

This invention relates to telephone systems and more particularly to connecting circuits employed in extending connections from subscribers' lines terminating in a plurality of connecting terminals.

Among the objects of this invention is to simplify and improve the connecting circuits of the above mentioned type.

A feature of this invention resides in the provision of a relay in a connecting circuit which responds to the insertion of the answering plug of the connecting circuit into the jack of a calling line for connecting the operator's telephone equipment to the connecting circuit, and for operatively associating ringing equipment, common to a plurality of connecting circuits, to the calling end of the connecting circuit employed.

Another feature of the invention resides in the provision of a relay in a connecting circuit responsive to the connection of the answering plug with a calling line to cause the connection of the operator's testing equipment and the common ringing equipment with the connecting circuit, and responsive to the disconnection of the calling party to remove the control of the supervisory signaling apparatus of the connecting circuit from the calling party.

A still further feature relates to a relay in a connecting circuit which responds to the actuation of a key common to a plurality of connecting circuits for causing the application of ringing current to the calling end of the connecting circuit, and responds to the actuation of another key common to the connecting circuits to prevent the application of ringing current to the calling end of the connecting circuit.

It is believed the invention will be best understood from the following detailed description made with reference to the accompanying drawings.

In the drawings:

Fig. 1 shows a calling line A terminating at a central exchange in a plurality of answering jacks and in a multiple jack, a four party line D, having similar terminals at the central exchange, and the cord circuit C employed in extending a connection between the lines A and D.

Fig. 2 shows an operator's telephone set and testing equipment O, together with the ringing equipment necessary in signaling the different parties on the line D (Fig. 1).

In the following description the subscriber on the line A will be considered the calling subscriber and any one of the parties on the line D, the called subscriber. The signaling of each party on the line D, however, will be described in detail.

Upon initiating a call, the subscriber at station A removes the receiver from the switchhook and establishes an obvious circuit for the line relay 3, which thereupon operates. Relay 3 in operating, completes a circuit extending from grounded battery, through the filaments of lamps 8 and 9, which lamps are located in front of different operators at the central office, any one of which operators may answer the call. The lamps are illuminated notifying all the operators that a call is awaiting attention.

It will be assumed that at this time the operator at the position at which lamp 8 is located is free to handle the incoming call. This operator, therefore, inserts plug 11 associated with the cord circuit C into jack 12 located at her position and associated with the calling subscriber's line.

Upon the insertion of plug 11 into jack 12, a starting relay 20 common to the link circuits of the operator's position, operates over a circuit from ground, through the winding of cut-off relay 4, sleeve contacts, jack 12 and plug 11, winding and contact 64 of relay 14, contacts 65 of relay 52, conductor 175, contacts 66 of relay 31, contacts 67 of relay 32, winding of relay 20, contacts 68 of relay 35 to grounded battery over the contacts 69 of relay 31. Relays 4 and 14 are marginal and do not receive sufficient current at this time to operate. Relay 20 in operating, causes the operation of relay 32. Relay 32 in attracting its inner left hand armature, opens at its contacts 67, a shunt path normally connected around the polarized relays 30 and 40, connects ground between resistance 19 and relay 20 and at its outer left hand armature connects 100 grounded battery through resistance 18, between relay 40 and resistance 19. With relay 32 operated and with ground and grounded battery connected to resistances 19 and 18, as described, a potentiometer circuit arrangement is formed. The closure of contacts 173 of relay 32 causes relay 20 to remain operated through the contacts 68 of relay 35 and contacts 69 of relay 31 to grounded battery.

105
110

Since the line has been assumed to be free, current will now flow through relays 30 and 40 over conductor 75 in a direction such as to operate relay 30. Relay 40 does not operate at this time as the current flow through its winding is not in the proper direction. The current path for relay 30 may be traced from ground through the winding of cut-off relay 4, sleeve contacts of jack 12 and plug 11, winding and contacts 64 of relay 14, contacts 65 of relay 52, conductor 175, contacts 66 of relay 31, windings of relays 30 and 40, contacts 73 of relay 32, and thence through one arm of the potentiometer circuit, including resistance 18 to grounded battery. It will be noted that current also flows at this time through resistance 18 and resistance 19 (forming the other arm of the potentiometer circuit) to ground, but this current is ineffectual.

Relay 30 in operating, completes a circuit for relay 31, over a path from grounded battery, through the armature and contact of relay 30, left hand winding of relay 31 to ground on the right hand contacts of relay 32. Relay 31 thereupon operates and locks over a path extending from grounded battery, left hand alternate contacts and winding of relay 31 to ground at the right hand contacts of relay 32. Relay 31 in operating, opens at its contacts 69 the energizing circuit for relay 20, whereupon relay 20 releases, which in turn releases relay 32. Relay 31 in operating, also opens at its contacts 66 the circuit for relay 30, whereupon this relay releases. In attracting its right hand armature relay 31 connects its right hand winding and resistance 17 in multiple to conductor 175. This circuit being established before the release of relay 32, relay 31 remains operated after the release of relay 32.

The connection of grounded battery through the right winding of relay 31 and resistance 17 in parallel, increases the current flow over the conductor 175 sufficiently to permit the operation of marginal relays 14 and 4.

Relay 14 in operating locks over a path extending from ground, through the winding of cut-off relay 4, sleeve contacts of jack 12 and plug 11, winding and contacts 61 of relay 14, to grounded battery at the contacts 170 of relay 52. At its armatures 33 and 34, relay 14 connects grounded battery and ground to the ring and tip of the answering end of the cord circuit C through the winding of supervisory relay 13, which relay thereupon operates over the closed subscriber's line loop. In attracting its armature, relay 13 connects battery to a contact of relay 52 for future use. Relay 22 now operates in a circuit extending from grounded battery, armature 33 and front contacts of relay 14, conductor 37, winding of relay 22,

back contact and right hand armature of relay 85, conductor 38 to ground at the contact 39 of key 41.

Cut off relay 4 operating in the circuit hereinbefore traced, removes the line relay 3 from the calling line, whereupon this relay releases and opens the circuit for lamps 8 and 9, which thereupon are extinguished.

Relay 22 in operating, as described, connects at its armatures 42 and 43, the listening leads from the operator's telephone set, to the cord circuit C. At its armature 44, relay 22 prepares a circuit for marginal relay 60 and for relay 97 in the operator's position equipment. At its armatures 45 and 46, relay 22 prepares circuits which will hereinafter be traced.

The operator's headset being connected across the talking conductors of the cord circuit, the operator ascertains the nature of the desired connection. Upon learning that a party on the line D is desired, the operator makes the usual busy test and if the desired line is idle, she inserts plug 47 into jack 48, of the called line.

The insertion of plug 47 into jack 48 causes relay 52 to operate over an obvious sleeve circuit including the winding of cut-off relay 56. At its armature 172, relay 52 causes calling supervisory lamp 49 to be illuminated over an obvious circuit, and also connects battery to the back contact of the tripping relay 84 and to the winding of relay 85. The battery at the back contact of relay 84 flows through the winding of marginal relay 60, front contact and armature 44 of relay 22, conductor 54 to ground through the winding of relay 97. Relay 60 does not receive sufficient current at this time to operate. Relay 97, however, operates to cause the ringing pilot lamp 98 to glow in an obvious circuit.

In opening its contacts 170, relay 52 disconnects battery from the locking circuit of relay 14 hereinbefore traced, and in closing its contacts 173, it substitutes the battery associated with the front contact and supervisory relay 13 therefor, so that relay 14 is now locked under the control of relays 52 and 13. The make-before-break contacts of relay 52 and the slow releasing characteristics of relay 14 enable this battery transfer to be made without causing relay 14 to release its armatures. At its contacts 174, relay 52 also connects battery to the winding of relay 22.

If the calling subscriber asks for a connection with "party W", the operator actuates key W' for an instant to cause the desired party to be signaled automatically.

The actuation of key W' causes relay 75 to be operated. At its contacts 59, relay 75 prepares the peg-count relays 92 and 93 for actuation. It may be stated here that the peg-count circuit is employed only at certain

intervals when a check on the number of calls handled by the operator is desired, and when such a check is to be made, key 155 is actuated, so that upon the actuation of any 5 of the ringing keys, or the trunk key T, the circuit for relays 92 and 93 will be completed, and the peg-count device actuated. At its contacts 57, relay 75 connects ground to the lead 54 thereby shunting relay 97 to extinguish the pilot signal 98 and to cause marginal relay 60 to receive sufficient current to operate. At its contacts 58, relay 75 causes relay 23 to operate to disconnect the operator's telephone set from the cord circuit. 10

Relay 60 in attracting its armature 24, locks under the control of both relays 84 and 52. At its armatures 25 and 26, it removes the short circuit normally around the ring-back-tone condensers 88 and 89. In attracting its armature 25, relay 60 connects the ground on the outer left hand armature of relay 70 to the tip side of the calling end of the cord circuit C. At its armature, 27, relay 60 completes the energizing circuit for 15 relay 85, which circuit was initiated by the operation of relay 52. When relay 85 operates, a circuit for a special code of ringing current is established which may be traced from the ringing current source 190 (Fig. 2) through the interrupter 28, conductor 29, contacts 62 of relay 63, winding of tripping relay 84, front contact and left hand armature of relay 85, outer right hand armature and back contact of relay 70, front contact and armature 26 of relay 60, ring contacts of plug 47 and jack 48, through the bells at the subscriber's station R to ground. 20

25 The condensers 88 and 89 serve to complete a path back to the calling subscriber's line, thereby enabling the subscriber to hear the ringing signal.

Should the "party R" be desired by the calling subscriber, the operator would momentarily actuate key R', whereupon relay 45 474 operates. At its contacts 177, relay 74 causes relay 63 to operate in a circuit extending from grounded battery over the armature 172 and front contact of relay 52, back contact and armature of tripping relay 84, winding of relay 63, conductor 71, front contact and armature 46 of relay 22, conductor 77 to ground on the contacts 177 of relay 74. At its contacts 78, relay 74 causes relay 75 to operate causing the closure of the peg-count circuit, the shunting of relay 97, the extinguishing of pilot lamp 98 and the operation of relays 60 and 23 as hereinbefore described.

Relay 63 in attracting its armature 79, locks up under the control of relays 84 and 52. At its armature 82, relay 63 prepares a circuit for relay 83, and at its contact 86, prepares the connection of lead 87 to the ring side of the cord which will be completed 30 when relay 83 operates.

At the proper interval, battery from the ringing equipment will be connected to the lead 90 through interrupter 91, whereupon relay 83 operates in a circuit extending from grounded battery on the lead 90, normal 70 make-before-break contacts of relay 83 winding of relay 83, armature 82 and front contact of relay 63 to ground. Relay 83 operates and in attracting its outer armature, locks up independently of lead 90. At its inner 75 armature, relay 83 causes a special current code to be connected to the ring side of the cord. This path may be traced from the ringing current source 190 (Fig. 2) over the interrupter 94, conductor 87, front contact 80 and inner armature of relay 83, contacts 86 of relay 63, winding of relay 84, left hand armature and front contact of relay 85, conductor 67, outer right hand armature and back contact of relay 70, front contact and armature 26 of relay 60, ring contacts of plug 47 and jack 48 and thence through the bells at the subscriber's station R to ground.

If the operator receives a request for "party J", she momentarily actuates the corresponding key J', whereupon relay 73 operates to cause the functioning of the peg-count equipment, to shunt out relay 97, extinguish the pilot lamp 98 and operate relays 23 and 60, in the same manner as described in connection with the actuation of key R'. 15

At its contacts 96, relay 73 connects ground to the conductor 99 causing relay 70 to operate in a circuit extending from grounded battery, over the right hand armature and front contact of relay 52, back contact and armature of relay 84, right hand winding of relay 70, front contact and armature 45 of relay 22, conductor 99 to ground on the contacts 96 of relay 73. 20

Relay 70 at its outer left hand armature connects ground to the ring side of the cord C by way of its front contact, and the front contact and armature 26 of relay 60. At its inner left hand armature, relay 70 locks. At its outer right hand armature, relay 70 prepares a circuit for transmitting ringing current over the tip side of the cord, and at its inner right hand armature, it establishes an energizing circuit for relay 85 to grounded battery on the front contact and armature 172 of relay 52. After an interval, slow operating relay 85 operates and locks to ground on the normal contact 39 of key 41. At its left hand armature, relay 85 completes the circuit to the tip conductor of the cord which circuit was initiated by relay 70 at its outer right hand armature. 25

Ringing current now passes through interrupter 28 over conductor 29, contact 62 of relay 63, winding of tripping relay 84, front contact and inner left hand armature of relay 85, conductor 67, outer right hand armature and front contact of relay 70, front contact and armature 25 of relay 60, tip con- 30

tacts of plug 47 and jack 48 through the bells at the subscriber's station J to ground.

To signal "party M", the operator momentarily actuates key M' causing relay 72 to operate. Relay 72 in operating, causes both relays 73 and 74 to operate, which in turn causes relay 75 to operate. Relay 75 at its contacts 59 causes the peg-count equipment to function while at its contacts 57, it shunts out relay 97 causing the extinguishment of the ringing pilot lamp 98, and the operation of relay 60. At its contacts 58, relay 75 operates relay 23 to disconnect the operator's telephone set from the cord circuit. Relay 74 at its contact 77 causes relay 63 to operate as described in connection with the actuation of key R'. Relay 63 performs the same functions as previously described, namely locks itself under control of relays 84 and 52 and prepares relay 83 for operation.

Relay 73 at its contacts 96 causes relay 70 to operate and lock under the control of relays 84 and 52, to connect ground to the ring conductor of the cord by way of the front contact and armature 26 of relay 60 and to prepare the tip side of the cord for the transmission of signaling current thereover.

At the proper interval, battery will be connected to conductor 90 by way of interrupter 91, whereupon relay 83 operates to ground on the front contact and armature 82 of relay 63. Relay 83 in operating, locks under control of relay 63.

The circuit for ringing current may now be traced from the ringing current source 190 through interrupter 94, conductor 87, front contact and inner armature of relay 83, contacts 86 of relay 63, winding of relay 84, left hand armature and front contact of relay 85, outer right hand armature and front contact of relay 70, front contact and armature 25 of relay 60, tip contacts of plug 47 and jack 48 through the bells at the subscriber's station M to ground.

Should the operator neglect to depress the ringing key such as M', J', R' or W' for a sufficient length of time or to a sufficient extent, the ringing pilot lamp 98 will remain lighted. Upon noting the continued illumination of lamp 98, the operator will know that the ringing equipment has not functioned and she will again actuate the ringing key.

In each of the preceding ringing operations relay 85 in operating, opened the circuit for relay 22 which in releasing disconnected the operator's telephone set and the common ringing leads 54, 48 and 99 from the cord circuit.

Although ringing current passes through the winding of relay 84, in each of the above ringing operations, this relay being marginal, does not operate on these occasions.

When the called party answers the signal, tripping relay 84 operates and opens the locking circuit of relays 60, 70 and 63 releasing them if operated. The operation of tripping relay 84 is effected in the following manner. When the called subscriber such as the subscriber at station J, removes the receiver from the switchhook, the condenser 165 associated with the sub-station equipment is short-circuited by the switchhook contacts, thereby reducing the resistance of the ringing current circuit to such an extent as to permit marginal relay 84 to operate. The ground connected to the tip or ring conductors of the cord circuit by the outer left hand armature of relay 70 depending on whether or not this relay is operated, serves as a return path for the ringing current when the subscriber removes the receiver from the switchhook.

The release of relay 63 as above mentioned, causes relay 83 to release if operated. Relay 60 in restoring, as above mentioned, again shunts the ring-back-tone condensers 88 and 89 and renders the tip and ring conductors of the calling end of the cord circuit C continuous. Upon the release of armatures 26 and 24 of relay 60, the calling supervisory relay 100 operates from battery, associated with the repeating coil 15, over the closed subscriber's line loop. Relay 100 in operating, causes lamp 49 to be extinguished. Should the called subscriber at any time desire to flash, he may do so by actuating his receiver switchhook, thereby interrupting the closed line loop, and causing relay 100 to be intermittently deenergized, whereupon the lamp 49 flashes.

At the termination of the conversation, the called subscriber in restoring his receiver, will cause lamp 49 to glow steadily, which serves as a disconnect signal to the operator.

When the calling subscriber at station A replaces his receiver on the switchhook, the circuit for supervisory relay 13 is opened, whereupon this relay releases. Relay 13 in retracting its armature, opens the locking circuit for relay 14. This relay thereupon restores its armatures. Relay 14 in retracting its armature 33, causes the answering supervisory lamp 55 to be illuminated in a circuit extending from grounded battery, armature 33 and back contact of relay 14, filament of lamp 55, front contact and right hand armature of relay 85, conductor 38, to ground on the contacts 39 of key 41. In retracting its armatures 33 and 34, relay 14 disconnects ground and battery from the answering end of the cord circuit. With supervisory relay 13 deenergized, the circuit for cut-off relay 4 is also opened, whereupon this relay releases and in retracting its armatures, reconnects the line relay 3 to the calling line. Should the calling party desire

to recall before the operator removes the plug 11 from jack 12 the call comes in on one of the multiple answering jacks in the same manner as described in connection with a new call originating at the station A.

Upon receipt of a disconnect signal as described, the operator removes plug 11 from jack 12, and plug 47 of jack 48. The removal of plug 11 from jack 12 at this time 10 has no effect on the cord circuit equipment, since all relays depending upon the connection of plug 11 with jack 12 for operation have been released.

Upon the removal of plug 47 from jack 15 48, relays 52 and 56 are deenergized. Relay 56 in retracting its armatures, reconnects the line relay 53 to the called line D. Relay 52 in retracting its armature 172, disconnects battery from the circuit including the 20 filament of calling supervisory lamp 49, whereupon this lamp is extinguished. Relay 52 also disconnects battery from the winding of relay 85, whereupon this relay releases, and opens the circuit for calling 25 supervisory lamp relay 55, whereupon this lamp is extinguished. The cord circuit equipment is now in normal condition.

On a connection over a trunk circuit (not shown) to which ringing current is not to be 30 applied the operator will depress the trunk key T after having inserted the plug 47 into the jack of the trunk (not shown) it now being assumed that the answering plug 11 has already been inserted into the jack, such as

35 12, of a calling line. The trunk circuit comprises at its outgoing end simply a tip and ring conductor connected to a jack such as 48 and a sleeve conductor having a suitable resistance therein. Such an arrangement is 40 so old and well known that it is not deemed necessary to show it. Upon the insertion of plugs 11 and 47 into jack 12 and the jack of an outgoing trunk circuit respectively, the cord circuit equipment associated with 45 the answering end, functions in the same manner as hereinbefore described. The operator then actuates the trunk key T causing relay 76 to operate. Relay 76 at its contacts 110, causes the peg-count equipment to function as in the previous operations. At is contacts 111, relay 76 connects ground to the conductor 99 which causes relay 70 to operate in a circuit extending from grounded battery, armature 172, and front contact of 55 relay 52, back contact and armature of relay 84, both windings of relay 70, front contact and armature 45 of relay 22, conductor 99 to ground on the contacts 111 of relay 76. Relay 70 operates in this circuit and locks 60 thereby removing its control from relay 22.

Unless relay 60 is operated, relay 70 performs no ringing function. At its right hand armature, relay 70 causes relay 85 to operate in an obvious circuit. Relay 85 65 locks under the control of key 41 and opens

the circuit for relay 22 which thereupon releases, causing the disconnection of the common ringing and listening leads from the cord circuit.

It is therefore apparent that by the particular arrangement shown, applicant has devised a system wherein an operator performs the same operations on both types of connections, one requiring ringing by the operator and the other which requires no ringing by the operator. 70 75

Should the calling party make a request for another party on the same line, the operator will instruct him to replace his receiver on the switchhook. When the operator 80 hears the disconnect click, caused by the placing of the receiver on the switchhook, she removes the plug 11 from the answering jack 12 and replaces it with the calling plug 47. 85

Upon this operation, relay 52 operates in an obvious sleeve circuit causing relay 22 to operate to connect the common ringing and listening leads to the calling end of the cord circuit. The operator then actuates the 90 key corresponding to the party desired to initiate the ringing signal. When the ringing starts, the relay 22 releases as hereinbefore described to remove the common ringing and listening leads from the cord. 95 Should the calling party come back on the connection too soon, the tripping relay 84 is operated as hereinbefore described to trip the ringing current.

If for any reason an operator, after having inserted her answering plug into the jack of a calling line, should desire to release her talking and testing equipment and the common ringing equipment without plugging into the called line she may do so 100 105 by depressing key 41 thereby opening the energizing circuit for relay 22 which releases to perform the desired operations. By this arrangement it is unnecessary for the operator to release the calling subscriber's line on such an occasion. 110

What is claimed is:

1. In a telephone system, a calling line, a called line, a plurality of connecting circuits, an operator's telephone set common to said connecting circuits, ringing control equipment common to said connecting circuits, means responsive to the connection of one end of one of said connecting circuits with said calling line for connecting said 115 telephone set to said connecting circuit and for operatively associating said ringing control equipment therewith and means responsive to the connection of the other end of said connecting circuit with said called 120 line, and the actuation of said ringing control equipment, to cause said telephone set and said ringing control equipment to be disconnected from said connecting circuit. 125

2. In a telephone system, a calling line, a 130

- called line, a plurality of connecting circuits having answering and calling ends, an operator's telephone set common to said connecting circuits, ringing control equipment common to said connecting circuits, means responsive to the connection of the answering end of one of said connecting circuits with said calling line for connecting said telephone set to said connecting circuit and for operatively associating said ringing control equipment with the calling end thereof and means responsive to the connection of the calling end of said connecting circuit to said called line and the actuation of said ringing control equipment to cause said telephone set and said ringing control equipment to be disconnected from said connecting circuit. 6. In a telephone system, a calling line, a called line, a plurality of connecting circuits having answering and calling ends, an operator's set common to said connecting circuits, ringing control equipment common to said connecting circuits, a relay for each of said connecting circuits operated in response to the connection of one of said connecting circuits with said calling line, means responsive to the operation of said relay for connecting said telephone set with said connecting circuit and for operatively associating said ringing control equipment therewith and means responsive to the actuation of said ringing control equipment to cause said telephone set and said ringing control equipment to be disconnected from said connecting circuit. 7. In a telephone system, a calling line, a called line, a plurality of connecting circuits, an operator's telephone set common to said connecting circuits, ringing control equipment common to said connecting circuits, a sleeve relay for each of said connecting circuits, operated in response to the connection of one end of one of said connecting circuits with said calling line, and means responsive to the operation of said sleeve relay for connecting said telephone set with said connecting circuit and for operatively associating said ringing control equipment therewith and means jointly responsive to the connection of the other end of said connecting circuit with said called line and the actuation of said ringing control equipment to cause the disconnection of said telephone set and said ringing control equipment from said connecting circuit. 8. In a telephone system, a calling line, a called line, a plurality of connecting circuits, an operator's telephone set common to said connecting circuits, ringing control equipment common to said connecting circuits, a relay for each of said connecting circuits responsive to the connection of the answering end of one of said connecting circuits with said calling line for connecting said telephone set to said connecting circuit and for operatively associating said ringing control equipment with the calling end thereof and means jointly responsive to the connection of the calling end of said connecting circuit to said called line and the actuation of said ringing control equipment to cause said telephone set and said ringing control equipment to be disconnected from said connecting circuit. 9. In a telephone system, a calling line, a called line, a plurality of connecting circuits, an operator's telephone set common to said connecting circuits, ringing control equipment common to said connecting circuits, a relay for each of said connecting circuits operated in response to the connection of one end of one of said connecting circuits with said calling line, and a second relay controlled by said sleeve relay for connecting said telephone set with said connecting circuit and for operatively associating said ringing control equipment therewith and means jointly responsive to the connection of the other end of said connecting circuit with said called line and the actuation of said ringing control equipment to cause the disconnection of said telephone set and said ringing control equipment from said connecting circuit. 10. In a telephone system, a calling line, a called line, a plurality of connecting circuits, an operator's telephone set common to said connecting circuits, ringing control equipment common to said connecting circuits, a sleeve relay for each of said connecting circuits, operated in response to the connection of one end of one of said connecting circuits with said calling line, and a second relay controlled by said sleeve relay for connecting said telephone set with said connecting circuit and for operatively associating said ringing control equipment therewith and means jointly responsive to the connection of the other end of said connecting circuit with said called line and the actuation of said ringing control equipment to cause the disconnection of said telephone set and said ringing control equipment from said connecting circuit.

the connection of the other end of said connecting circuit with said called line and the actuation of said ringing control equipment to cause said telephone set and said ringing control equipment to be disconnected from said connecting circuit.

9. In a telephone system, a calling line, a called line, a connecting circuit interconnecting said lines and having calling and answering ends, a sleeve relay associated with the answering end of said connecting circuit operated in response to the connection of the answering end of said connecting circuit with said calling line, a supervisory relay operated in response to the operation of said sleeve relay, a locking circuit for said sleeve relay controlled by said supervisory relay and established in response to the connection of the calling end of said connecting circuit with said called line, a supervisory circuit controlled by said sleeve relay and completed in response to the connection of the calling end of said connecting circuit with said called line, a supervisory signal and circuit connections whereby in response to the restoration of the receiver on the calling line said supervisory signal is actuated, said supervisory relay is removed from said connecting circuit and the locking circuit for said sleeve relay opened.

10. In a telephone system, a calling and a called line, an operator's link circuit having manual connection terminals for connecting with said lines, a supervisory relay in said link circuit, a sleeve relay associated with each of the manual connection terminals of said link circuit, one of said sleeve relays controlled over one of the connected lines for operatively disassociating the station of said line from said link, and a holding circuit for said one sleeve relay including contacts of each of the sleeve relays and said supervisory relay.

45 11. In a telephone system, a calling line, a called line, a connecting circuit interconnecting said lines, a supervisory signal, a supervisory relay normally disconnected from said connecting circuit, a second relay responsive to the connection of said connecting circuit with said calling line for connecting said supervisory relay to said connecting circuit whereby said supervisory relay operates to effect a locking circuit for said second relay and responsive to a disconnection by the subscriber on said calling line for actuating said signaling device and removing said supervisory relay from said connecting circuit.

60 12. In a telephone system, a calling subscriber's station, a called subscriber's station, a cord circuit interconnecting said stations, a relay associated with said cord circuit and operated in response to the connection of said cord circuit with said call-

ing station, a signaling device controlled by said relay, a locking circuit for said relay controlled from said calling subscriber's station, and means controlled at said calling station for interrupting said locking circuit whereupon said signaling device is actuated and removed from further control of the calling station.

13. In a telephone system, a calling subscriber's line, a connecting circuit having answering and calling ends, ringing equipment including a plurality of keys, a ringing current source, means responsive to the connection of the answering end of said connecting circuit with said calling line for associating said ringing equipment with the calling end of said connecting circuit, and a plurality of relays in said connecting circuit operated in response to the actuation of one of said keys for transmitting a ringing current from said source over the calling end of said connecting circuit, one of said relays being also responsive to the actuation of another of said keys for preventing the transmission of ringing current.

14. In a telephone system, a calling subscriber's line, a connecting circuit having answering and calling ends, ringing equipment including a plurality of keys for said connecting circuit, a ringing current source, means responsive to the connection of the answering end of said connecting circuit with said calling line for associating said ringing equipment with the calling end of said connecting circuit, and means including a relay in said connecting circuit responsive to the actuation of one of said keys for transmitting ringing current from said source over the calling end of said connecting circuit, said relay being also responsive to the actuation of another of said keys to prevent the transmission of ringing current.

15. In a telephone system, a calling line, connecting circuits, an operator's testing equipment, ringing equipment common to a plurality of said connecting circuits, supervisory signaling apparatus for said connecting circuits, a relay in each of said connecting circuits responsive to the connection of one thereof with said calling line to connect said testing equipment and said ringing equipment to the connecting circuit employed, and means controlled by said relay when the subscriber and said calling line disconnects, for removing the control of said supervisory apparatus from the calling line.

16. In a telephone system, a calling line, a called line, a plurality of connecting circuits having answering and calling plugs, a relay operated in response to a connection of the answering plug of said connecting circuits with said calling line, a plurality of ringing keys common to said plurality of connecting circuits, an operator's telephone set, said keys and said telephone set being

associated with one of said connecting circuits when said relay is operated, and means responsive to the connection of the calling plug of said connecting circuit with said 5 called line and the actuation of one of said keys, for disassociating said ringing keys and said telephone set from said connecting circuit.

17. In a telephone system, a calling subscriber's line, a called subscriber's line, a cord circuit having answering and calling ends for interconnecting said lines, a sleeve relay in said cord circuit operated in response to the connection of the answering 10 end of said cord circuit with said calling subscriber's line, a supervisory relay associated with said cord circuit and operatively connected therein in response to the operation of said sleeve relay, and a holding circuit for said sleeve relay including 15 operated contacts of said supervisory relay completed in response to the connection of the calling end of said cord circuit with said called line and broken to disconnect said supervisory relay from its operative connection 20 in said cord circuit in response to replacement of the calling subscriber's receiver on the switchhook.

18. In a telephone system, a calling telephone line, an operator's link circuit having 30 a manual connection terminal for connecting with said line, an operator's telephone set, means for connecting said set to said link circuit, a sleeve relay controlled over the connected line for controlling said means 35 for connecting said set to said link circuit and for operatively disassociating the station of said line from said link, and a holding circuit for said relay including a contact of said manual connection terminal. 40

19. In a telephone system, a calling telephone line, an operator's link circuit having 45 a manual connection terminal for connecting with said line, a supervisory relay in said link circuit, a signal controlled thereby, a sleeve relay controlled over the connected line for operatively disassociating the station of said line from said link and a locking circuit for said sleeve relay including a contact of said supervisory 50 relay.

In witness whereof, I hereunto subscribe my name this 27th day of November A. D., 1923.

CLARENCE B. FOWLER.
